Fig. 5

FIGURE 1 is a perspective view of a cover for an electrical apparatus enclosing case showing my new design with shallow sides;

FIG. 2 is a front elevational view of the cover shown in FIG. 1;

FIG. 3 is a cross-sectional view on the line 3-3 of FIG. 2;

FIG. 4 is a perspective view of a cover for an electrical apparatus enclosing case showing my new design with deep sides, and

FIG. 5 is a cross-sectional view taken on the line 5-5 of FIG. 4.

The dominant features of my design reside in the portions shown in solid black lines in the drawings, and the dot-dash line showing of other portions of an enclosing case are for purposes of illustration only.

I claim:

The ornamental design for a cover for an electrical

apparatus enclosing case, substantially as shown and described.
